COMBINED GAS LIGHTER AND DETACHABLE BASE THEREFOR

Gerard Philippe Encausse, 46 Boulevard du Montparnasse,
Paris 15eme, France

Filed Dec. 9, 1969, Ser. No. 20,418

Term of patent 3½ years

Int. Cl. D27—05

U.S. Cl. D48—27

FIG. 2

FIG. 1

FIG. 4

FIG. 3

FIG. 5

FIG. 1 is a side elevational view of a combined gas lighter and detachable base therefor embodying my new design with the gas lighter fixed in the base;

FIG. 2 is a top plan view thereof;

FIG. 3 is a bottom plan view thereof;

FIG. 4 is a perspective view thereof with the gas lighter withdrawn from the base for purposes of disclosure;

FIG. 5 is a perspective view thereof in the position of FIG. 1.

I claim:

The ornamental design for a combined gas lighter and detachable base therefor, as shown and described.
